UNITED STATES PATENT OFFICE.

LEONARD DYDYNISKI, OF BUENA VISTA, OHIO.

BURIAL-VAULT.

SPECIFICATION forming part of Letters Patent No. 325,826, dated September 8, 1885.

Application filed June 16, 1885. (Model.)

To all whom it may concern:

Be it known that I, LEONARD DYDYNISKI, of Buena Vista, in the county of Scioto and State of Ohio, have invented a new and Improved Burial-Vault, of which the following is a full, clear, and exact description.

My invention relates to a vault or receptacle to be placed in the grave to receive the coffin or casket containing the dead body.

10 The object of the invention is to provide a practical grave-vault, of stone or other indestructible material, which may be made air and water tight, and which will be locked by suitable binding-iron, so that the lid cannot be taken off or the coffin or body removed without first breaking the slabs composing the vault.

15 The invention consists of the construction, arrangement, and combination of parts, all as hereinafter described and claimed.

Reference is to be had to the accompanying drawings, forming part of this specification, in which similar letters of reference indicate corresponding parts in all the figures.

20 Figure 1 is a plan view of my new and improved grave-vault with the cover or lid secured thereon. Fig. 2 is a longitudinal sectional elevation of the same on the line $x-x$ of Fig. 1; and Figs. 3 and 4 are transverse sectional elevations taken, respectively, on the lines $y-y$ and $z-z$ of Fig. 2.

25 The vault is composed of the bottom slab, a , side pieces, $b b$, end pieces, $c c$, and lid or cover d , all preferably of stone. When these parts are put together in the grave to form the vault, they are held by the bands or **U**-shaped pieces $e e$, of iron, and the locking cross-pieces $f f$, also of iron. The side pieces, $b b$, are kept from slipping or tipping inward 30 by suitable stops, $g g$, formed by rabbeting the bottom slab, a , and lid d . The end pieces, $c c$, are held in place by corresponding grooves, h , made in the bottom, top, and side pieces of the vault, as will be understood from Fig.

35 2. The **U**-irons e are held in place by being fitted into grooves i , made in the lower surface of the bottom slab, a ; and the locking irons f are held in place by being fitted into grooves j , made in the upper surface of the lid 40 or cover d . The extremities of the **U**-irons e are provided with spring-catches, the heads

$k k$ of which are adapted to engage with notches $k' k'$, formed in the downwardly-bent ends $f' f'$ of the locking cross-pieces f , for locking the said cross-pieces securely to the irons e . 55 The said spring-catches are composed of the said heads k and the spring plates or arms k^2 , which are riveted to the inner surface of the irons e , as shown clearly in Fig. 4. The heads k of the spring-catches reach through openings $l l$, made in the irons e , and they are inclined or curved downward at their upper surfaces or edges, so that by simply pressing down upon the irons f the extremities will pass the heads k of the spring-catches and 60 cause the heads to enter the recesses k' , and thus effect the locking of the bars f .

In order that the spring-catches may be forced backward to permit the extremities of the cross-pieces f to thus pass the heads k , I 70 recess the side pieces, $b b$, of the vault, as shown at $m m$, Fig. 2, thus forming a space or clearance for the action of spring-catches. At the upper ends of the irons e are formed the projections or dowels $n n$, which enter corresponding small recesses, $n' n'$, made in the cross-pieces $f f$, which serve to prevent all lateral movement of the cross-pieces f and irons e . 75

Constructed as described, the vault may be 80 shipped in a "knockdown" state and set up in the grave. When the coffin or casket is placed in the vault, the cover or lid d will be put in place and the cross-pieces f placed over the lid and pressed down to engage with the 85 heads k of the spring-catches, where they will be held with perfect security, so that the cover or lid cannot be removed.

If desired, the seams of the vault may be 90 made water and air tight by plaster-of-paris or other cement.

Having thus described my invention, what I claim as new, and desire to secure by Letters Patent, is—

1. The burial-vault herein shown and described, consisting of the slabs $a b c d$, held together by the **U**-irons e and locking cross-pieces f , constructed to engage with locking-hooks attached to the extremities of the irons e , substantially as described. 95

2. The **U**-irons e , provided with spring-catches, in combination with the cross-pieces 100

f, formed with recesses *k*, to receive the locking-heads of the spring-catches, substantially as described.

3. The combination, with the bar or cross-piece *f*, formed with downward-bent ends *f'*, having recesses *k'* formed therein, of the **U**-iron *e*, having openings *l* in its ends, and spring-

catches secured to the inner surfaces of said ends, and having heads *K* projecting through the openings *l*, substantially as set forth.

LEONARD DYDYNISKI.
